GAME BOARD

Murray Wallace, 2115 Bragg Hill Drive, Mobile, Ala.

Filed June 13, 1960, Ser. No. 60,933

Term of patent 3½ years

(Cl. D34—5)

The figure in the drawing is a top plan view of a game board showing my new design.

The board is of conventional thickness and the drawing has been lined for color. The essential features of the design reside in the portions shown in solid lines.

I claim:

The ornamental design for a game board, as shown and described.
